ABSTRACT

A new *Lantana* plant named 'LANZ0003' particularly distinguished by the large sized, two-toned yellow flowers, with good floriferousness as a result of limited seed set, and a relatively compact habit with medium green foliage.

1 Drawing Sheet

1

Latin name of the genus and species of the plant claimed:
Lantana camara L.
Varietal denomination: 'LANZ0003'.

BACKGROUND OF THE NEW PLANT

The present invention comprises a new *Lantana*, botanically known as *Lantana camara* L., and hereinafter referred to by the variety name 'LANZ0003'.

'LANZ0003' is a product of a planned breeding program. The new cultivar has large sized, two-toned yellow flowers, with good floriferousness as a result of limited seed set, and a relatively compact habit with medium green foliage.

'LANZ0003' originates from a hybridization made in July 2007 in a controlled breeding program in Gilroy, Calif., USA. The female parent was unpatented, proprietary plant identified as 'G307-1' with a peach color, a larger flower size, more floriferousness and is about four days later to flower.

The male parent of 'LANZ0003' was identified as 'G292-1', an unpatented, proprietary plant with peach color, larger flowers, and a tighter compact habit. The resultant seed was sown in December 2007.

'LANZ0003' was selected as one flowering plant within the progeny of the stated cross in April 2008 in a controlled environment in Gilroy, Calif.

The first act of asexual reproduction of 'LANZ0003' was accomplished when vegetative cuttings were propagated from the initial selection in December 2008 in a controlled environment in Gilroy, Calif.

BRIEF SUMMARY OF INVENTION

Horticultural examination of plants grown from cuttings of the plant initiated in December 2008 in Gilroy, Calif., and continuing thereafter, has demonstrated that the combination of characteristics as herein disclosed for 'LANZ0003' are firmly fixed and are retained through successive generations of asexual reproduction.

'LANZ0003' has not been observed under all possible environmental conditions. The phenotype may vary significantly with variations in environment such as temperature, light intensity and day length.

2

A Plant Breeder's Right for this cultivar was applied for in Canada on Dec. 17, 2010, #10-7126. 'LANZ0003' has not been made publicly available more than one year prior to the filing of this application.

5 The following traits have been repeatedly observed and are determined to be basic characteristics of the new variety. The combination of these characteristics distinguishes this *Lantana* as a new and distinct variety.

10 **BRIEF DESCRIPTION OF THE PHOTOGRAPHS**

The accompanying photographic drawing shows typical flower and foliage characteristics of 'LANZ0003' with colors being as true as possible with an illustration of this type. The 15 photographic drawing shows a flowering plant of the new variety, and a close-up of the flowers.

DETAILED BOTANICAL DESCRIPTION

20 The plant descriptions, measurements and aforementioned photographs were taken in Gilroy, Calif. in April 2011 in a greenhouse. These plants were growing in 4.5 inch pots in a trial setting. The plants were about 12 weeks of age and were grown with several early sprays of Paclobutrazol, a plant growth regulator.

25 Color Chart used: Royal Horticultural Society Colour Chart (R.H.S.) 2001

TABLE 1

DIFFERENCES BETWEEN THE NEW VARIETY 'LANZ0003' AND A SIMILAR VARIETY		
	'LANZ0003'	'Balandimpea' (U.S. Plant Pat. No. 19,358)
35 Flower size:	Larger	Smaller
Quantity of flowers:	More floriferousness	Less floriferousness
Plant habit:	More compact	Less compact

40 Plant:

Form, growth and habit.—Relatively compact and bushy, well-branched with apical pinching enhancing the number of branches and results in a tighter plant habit.

<i>Plant height.</i> —13.0-16.0 cm.		<i>Lower surface.</i> —RHS 4D.
<i>Plant height (inflorescence included).</i> —16.0-17.0 cm.		<i>Petal length.</i> —0.4-0.6 cm.
<i>Plant width.</i> —35.0-40.0 cm.		<i>Petal diameter.</i> —0.4-0.6 cm.
Foliation:		<i>Apex.</i> —Mucronulate.
<i>Type.</i> —Opposite.	5	<i>Margin.</i> —Entire.
<i>Immature, leaf color, upper surface.</i> —RHS 137A but a little deeper.		<i>Shape.</i> —Obovate.
<i>Lower surface.</i> —Closest to RHS 137C.		<i>Degree of lobation.</i> —Moderate.
<i>Mature, leaf color, upper surface.</i> —RHS 137A but a little deeper.	10	<i>Texture, upper surface.</i> —Papillose.
<i>Lower surface.</i> —Closest to RHS 137C.		<i>Lower surface.</i> —Papillose.
<i>Length.</i> —5.6-6.1 cm.		<i>Corolla tube, color, outer surface.</i> —RHS 4C with overlaid hints of RHS 3C.
<i>Width.</i> —3.7-3.8 cm.		<i>Color, inner surface.</i> —RHS 8C to RHS 8D.
<i>Shape.</i> —Ovate.	15	<i>Corolla tube length.</i> —1.2 cm.
<i>Base shape.</i> —Attenuate.		<i>Diameter (at opening).</i> —0.2 cm.
<i>Apex shape.</i> —Acute.		<i>Corolla tube texture, outer surface.</i> —Pubescent.
<i>Margin.</i> —Serrulate.		<i>Inner surface.</i> —Glabrous.
<i>Texture, upper.</i> —Hirsute.		Bud (just before opening):
<i>Lower surface.</i> —Hirsute.		<i>Color.</i> —RHS 4C.
<i>Color of veins, upper surface.</i> —RHS 144A.	20	<i>Length.</i> —1.3-1.5 cm.
<i>Color of veins, lower surface.</i> —RHS 144B.		<i>Width.</i> —0.3.
<i>Petioles color.</i> —RHS 144A.		<i>Shape.</i> —Tubular.
<i>Petioles length.</i> —1.0-1.8 cm.		Bract:
<i>Diameter of petiole.</i> —0.2 cm.	25	<i>Color.</i> —RHS 137D.
<i>Texture.</i> —Hirsute; glandular hairs.		<i>Length.</i> —0.5 cm.
Stem:		<i>Diameter.</i> —0.2 cm.
<i>Quantity of main stems.</i> —4-6.		<i>Texture, upper surface.</i> —Glabrous.
<i>Color of stem.</i> —RHS 144A.		<i>Lower surface.</i> —Glandular hairs.
<i>Length of stem.</i> —2.0-15.0 cm.	30	Calyx:
<i>Diameter.</i> —0.2-0.3 cm.		<i>Number of sepals.</i> —5, fused sepals forming a short tube around the base of each floret.
<i>Length of internodes.</i> —0.5-1.8 cm.		<i>Color of sepals.</i> —RHS 144D.
<i>Texture.</i> —Hirsute; glandular hairs.		<i>Length of sepals.</i> —0.2-0.3 cm.
Inflorescence:		<i>Width of sepals.</i> —0.2 cm.
<i>Type.</i> —Umbel like, flattened semi-sphere the florets are sessile on an ovate receptacle.	35	<i>Apex shape.</i> —Acute.
<i>Blooming habit.</i> —Flowers continuously from spring through fall.		<i>Apex margins.</i> —Slightly fringed.
<i>Number of open flowers per inflorescence.</i> —About 24 with numerous buds.		<i>Texture, outer surface.</i> —Pubescent.
<i>Quantity of inflorescences per plant.</i> —About 13-15.	40	<i>Inner surface.</i> —Glabrous.
<i>Lastingness of individual blooms on the plant.</i> —About 4 weeks (depending on temperatures).		Reproductive organs:
<i>Fragrance.</i> —Slightly spicy.		<i>Pistil.</i> —1.
<i>Umbel horizontal diameter.</i> —About 5.0 cm.		<i>Length.</i> —0.2-0.3 cm.
<i>Umbel depth.</i> —About 2.5 cm.	45	<i>Style color.</i> —RHS 4D.
<i>Peduncle color.</i> —Between RHS 144A and RHS 144B.		<i>Style length.</i> —0.2 cm.
<i>Length of peduncle.</i> —6.5-7.5 cm.		<i>Sigma color.</i> —RHS N144A.
<i>Peduncle diameter.</i> —0.15 cm.	50	<i>Stamens.</i> —4.
<i>Texture.</i> —Hirsute; glandular hairs.		<i>Color of filaments.</i> —RHS 1D but lighter.
Corolla:		<i>Length filaments.</i> —0.4 cm.
<i>Floret form.</i> —Salver-shaped to shallow cup-shaped and zygomorphic, with a relatively long tube at the base.		<i>Anther color.</i> —RHS 199C.
Each flower subtended by a single bract.		<i>Length of anthers.</i> —0.1 cm.
<i>Floret horizontal diameter.</i> —1.0-1.1 cm.	55	<i>Pollen amount.</i> —Sparse.
<i>Floret depth.</i> —1.6 cm.		<i>Color of pollen.</i> —Not observed on this hybrid.
<i>Immature, color of petals, upper surface.</i> —RHS 6A with RHS 4C margins.		Fertility/seed set: Fertility/seed set has not observed on this hybrid.
<i>Lower surface.</i> —RHS 4D.		Disease/pest resistance: Disease/pest resistance has not been observed on this hybrid.
<i>Mature, color petals, upper surface.</i> —RHS 6B with RHS 4C margins.	60	What is claimed is:
		1. A new and distinct variety of <i>Lantana</i> plant named 'LANZ0003' substantially as illustrated and described herein.
